Isaac Burnell 821X.

The schedule referred to in these to follow Read and reading
part of the same containing a description in the words of
the said Isaac Burnell himself of his improvement in
the machine for propelling boats on canals and
steam waters.

To all to whom these presents shall come -

Be it known that I, Isaac Burnell of Elizabethtown in the
County of Franklin and State of Ohio have invented
a new and useful improvement in a machine for pro-
pelling boats on canals and steam water and that
the following is a full and exact description of the con-
struction and operation of said machine as invented by
me. At sun wheel A, eight or nine feet in diameter,
from side to side, twelve inches thick, formed into notches
as on the flywheel, and if necessary shall within sides
has its eye hung upon bearings &c. at the end of a substan-
tial bar B. about six feet long, said bar at the
wheel end being so divided as to pass each side of said wheel
etc. The opposite end of said bar has also a shaft C, pass-
ing through it within bearings &c. at right angles to the opposite sides
of said bar, from these bearings to other bearings D, correspond-
ing therewith on opposite sides of the wheel A, pass-
ing through said bar, so that the revolving of the shaft C. at the
end of the bar B. opposite will cause the wheel A to re-
volve. The wheel A. is intended to traverse the canal
carrying the water in its path, and of sufficient weight
so loaded as to take hold upon the bottom of the canal
and rising (up falling) freely accommodates the wheel
to the bottom, be it ever so uneven. The shaft being sup-
ported by suitable bearings D. & guides E. forms a simple & suffi-
ciently propulsive apparatus to carry off any size in
steam waters and may be used separately or in connection with
any kind of a wheel or hull.
